US00D615079S

(12) **United States Design Patent**
Masuyama et al.

(10) **Patent No.:** US D615,079 S
(45) **Date of Patent:** ** May 4, 2010

(54) **PERSONAL COMPUTER**

(75) Inventors: **Nobuharu Masuyama**, Yokohama (JP);
Hiroyuki Fujita, Tokyo (JP)

(73) Assignee: **Fujitsu Limited**, Kawasaki (JP)

(**) Term: **14 Years**

(21) Appl. No.: **29/309,729**

(22) Filed: **Sep. 29, 2008**

(30) **Foreign Application Priority Data**

Mar. 28, 2008 (JP) 2008-007951

(51) **LOC (9) Cl.** 14-02

(52) **U.S. Cl.** D14/315

(58) **Field of Classification Search** D14/315-323,
D14/341-346; D18/1, 2, 7, 11; 235/145 A,
235/145 R; 248/460; 345/156, 168, 169,
